SNOWPLOW

George C. Soule, South Portland, Maine, assignor
to Maine Steel Products Company, South
Portland, Maine, a corporation of Maine

Application January 19, 1932. Serial No. 587,517

3 Claims. (Cl. 37—44)

This invention relates to snow plows and particularly to a plow which combines in a single plow the advantages and avoids the disadvantages of the two different types of snow plow now commonly used in dealing with the two different snow conditions most usually encountered.

For patrol work on wide roads and with light snow, a one-way plow is generally considered most efficient, for the reason that the entire 10 blade of the plow pushes the snow one way and hence the entire blade may be used to make both the second cut as well as the first cut through the snow.

Where the snow is heavy, however, or where 15 drifts have accumulated, as frequently occurs, the efficiency of the one-way plow is almost entirely lost, due to the fact that the action of the one-way plow in pushing all the snow one way, creates so great a side draft as to make the 20 plow unmanageable on the road.

When these conditions of heavy snow and/or deep drifts prevail, therefore, it has been found more efficient to use a V-plow, because the V-plow will penetrate and go straight through the 25 heavy snow and/or drifts whereas the side draft which results when the one-way plow attempts to penetrate the same heavy snow and/or drifts tends to push the front wheels of the truck sideways and throw the truck off the road.

The V-plow, however, is not as efficient as the 30 one-way plow for patrol work duty on wide roads and in light snow.

My present plow combines in a single unit the advantages of both of these prior types of plow 35 in meeting the conditions for which each was particularly designed, while at the same time avoiding the disadvantages peculiar to each type when it was used under snow conditions for which the other was best adapted. As such, my 40 present plow is a plow of double purpose.

Superficially, my present plow resembles the familiar V-plow in general appearance, but is sharply distinguished therefrom in this respect, that the V nose is not only offset relative to the 45 major axis fore and aft of the plow, but that such offset itself is so carefully balanced relative to the plow axis as to give a plow of new result.

The offset V-plow itself is neither new in the art nor particularly effective of result on the 50 road, due to the fact that all such offset V-plows with which I am familiar have entirely lacked that balance which is so necessary if the plow is to perform efficiently its intended work.

In all such prior offset V-plows the two sides 55 or mold boards of the offset V have been of equal

angle with a line fore and aft of the plow, that is to say, the included angles of the offset V have always heretofore been equal to each other with the result that the projection of the cutter bars on the fore and aft line above mentioned have consequently been unequal.

This creates a one-sided or unequal push of the snow which seriously detracts from the efficiency of the plow. In other words, the side draft or sidewise push of the snow is out of balance and hence the usual offset equal-angled V-plow cannot fail to throw the wheels of the truck sidewise when bucking a drift.

With my plow, however, I have not only offset the V nose relative to the center line fore and aft of the plow, but I have so designed the V-nose itself as to introduce a factor of balance in the plow which it never heretofore possessed and by reason of which all tendency of the plow to create a one-sided or unequal push of the snow plow is absolutely avoided.

According to my concept, the sides of the V are disposed at different angles to the fore and aft line of the V at all elevations when the angles are compared in planes parallel to the ground so as to afford a wide-angled side and a narrow-angled side.

Inasmuch as the angle of the narrow side is a sharper angle (about 40 degrees) than that of the wide side (about 60 degrees) the resultant of the wide blunt angle and the narrow sharp angles becomes a balancing factor which balances the relatively greater side draft created by the sharp wedge of the narrow side to the relatively lesser side draft created by the blunter wedge of the wide side. By thus balancing side draft, I am able to penetrate straight through drifts with my plow which with the offset equal-angled V plow heretofore used caused the wheels of the truck to be thrown sidewise off the road.

More than this, the sharp-angled narrow side permits the fore and aft projection of the cutter bar and cutting surface of the plow on the narrow side to be made substantially equal to that of the cutting bar and cutting surface on the wide side of the plow so that both sides offer substantially equal sidewise resistance when the plow is pushed through the snow.

In connection with such a plow, I find it desirable under certain circumstances to provide the V nose with snow deflectors at the upper edges of the wide and narrow mold boards which deflectors are removable and replaceable as well as being adjustable for height according to the requirements of the particular fall of snow being plowed.

Such deflectors constitute a desirable additional continuation of the snow-throwing surfaces of the mold boards under certain conditions of plowing as well as preventing the snow from being 5 thrown onto the windshield of the truck or other propulsion vehicle.

Similarly, my present plow may be provided at its wide side with an adjustable wing element if desired, such wing constituting in effect a lateral continuation of the wide side surface of the plow nose.

In the accompanying drawing I have shown a form of offset V-plow, balanced as heretofore described, which I have found highly satisfactory 15 under actual conditions of service.

In such drawing:—

Fig. 1 is a plan view thereof.

Fig. 2 is a front view, and

Fig. 3 is a diagram.

20 The right and left hand edges of the roadway to be plowed are indicated at R and L, respectively, in Fig. 1, and the direction of travel of the plow therealong by the arrow.

My plow may conveniently be mounted in any 25 standard manner on a truck T, the center fore and aft line of which is indicated at A. The center fore and aft line of the offset V nose is indicated at B.

One side or mold board of my offset V nose, 30 here shown as the left side 10 is made shorter than the other side 11 but of sharper angle. The two mold boards of the plow therefore are at unequal angles to the fore and aft line of the V at all elevations when the angles are compared in planes parallel to the ground. The fore and aft projection of both the narrow side 10 and the wide side 11 are substantially the same, however, so as to equalize sidewise resistance. Both sides 10 and 11 terminate in substantially the 40 same transverse plane, indicated at P in Fig. 3.

Although not intending thereby to limit myself to any particular angles, I have indicated in Fig. 3 that the included angles formed by said narrow and wide sides of the V are respectively 40° and 45 60°. These angles seem to afford a most satisfactory balancing resultant, but obviously the sides of the V might be differently angled, depending upon many factors of which the relative lengths of the sides themselves is one. In fact it 50 should be clearly understood that any departure from the equi-angled V will tend toward balance of side draft, although the chosen angles might result in locating the rear ends of the mold boards in other planes than the transverse plane above 55 mentioned. For different conditions and to suit the requirements of different types of primary equipment it may be advisable to use any combination of unequal angles in the V and any

plane across the rear ends of the mold board except that which would be the resultant of an equi-angled V.

As heretofore explained, the combined effect of the relatively sharp angled narrow side 10 80 and the relatively blunter angled wide side 11 balances side pressure and prevents the plow from kicking sidewise off the road when bucking drifts.

Moreover, on the first trip through the snow, the sharper-angled left hand narrow side spreads less snow on the left hand side of the road, thus reducing interference with traffic, while on the second, or later trips, the wider angled right hand wide side 11 makes a cut which is substantially 85 50 percent wider than can be made by any ordinary V-plow of equivalent size.

Where desired the mold boards 10 and 11 may be continued upwardly by means of the deflector extensions 12 and 13 (Fig. 2). These are removably and adjustably secured to the mold boards in any suitable manner, as by bolts 14 set through the mold boards and into elongated slots 15 formed in the deflectors themselves. Such deflectors may be either straight or flat in surface or may follow the curvature of the mold boards. 90

Similarly, the wide side 11 of the plow nose may be extended laterally by means of the adjustable wing element 16 (Fig. 1) which is operatively connected at its front and rear ends in any usual manner to the plow frame and braced as at 17. 105

While particularly applicable to snow plows, the principles of my invention are by no means limited thereto, but on the contrary may be embodied in other plows for other uses.

Various modifications in the construction and 110 operation of my plow may be resorted to without departing from the spirit of my invention if within the limits of the appended claims.

What I therefore claim and desire to secure by Letters Patent is:—

1. In a truck propelled snow plow, a nose unit comprising a balanced offset V-member having the center of its V offset relative to the center fore and aft line of the propulsion vehicle and having its mold boards disposed at substantially 120 unequal angles to the fore and aft line of the V at all elevations when the angles are compared in planes parallel to the ground.

2. A nose unit as claimed in claim 1, wherein the mold boards are of unequal length and the 125 angle of the short mold board is a relatively sharp angle and that of the long mold board is a relatively blunt angle.

3. A nose unit as claimed in claim 1, wherein the mold boards are of unequal length but terminate in substantially the same transverse plane. 130

GEORGE C. SOULE.
